UNITED STATES PATENT OFFICE.

FREDERICK J. GLEASON, OF CAMBRIDGE, MASSACHUSETTS, ASSIGNOR OF ONE-HALF
TO MAX BROWN, OF BOSTON, MASSACHUSETTS.

RESILIENT HEEL LIFT.

Application filed June 3, 1920. Serial No. 326,282.

To all whom it may concern:

Be it known that I, FREDERICK J. GLEASON, a citizen of the United States, and resident of Cambridge, county of Middlesex, Commonwealth of Massachusetts, have invented an Improvement in Resilient Heel Lifts, of which the following description, in connection with the accompanying drawings, is a specification, like characters on the drawings representing like parts in each of the several views.

This invention relates to resilient heel lifts and more particularly to lifts of molded and vulcanized rubber or rubber composition. Heel lifts of this kind in common use have heretofore been produced and supplied to the trade either flat, or in a concavo-convex or like shape. The flat heel lift has the advantage that it is adapted to be fitted to a heel seat without distortion and without tendency to pull away from the securing nails throughout its period of service, but it has the objection that it is difficult to make a close joint at all points between it and the heel seat. Hence in applying flat rubber heel lifts it has been necessary to exercise considerable care in the fitting and to cement the lift to the heel seat carefully in order to prevent the appearance of a crack or the pulling away of the lift at certain points from the seat. This objection has led to the extensive use of rubber heel lifts molded to a normally concavo-convex or like shape which require to be pressed down from this shape and held flat against the heel seat by the securing nails. This has achieved the result of a constant pressure and close engagement of the lift edges against the heel seat but it has been subject to the serious objection that since the lift must be distorted from its normal shape in nailing it to the heel seat it is impossible either to make it lie perfectly flat against the attaching surface or to present a flat wearing surface. This has particularly been the case in the use of tough and live rubber, i. e., high grade stock, for the heel lifts and heel lifts of the concavo-convex type are hence constantly tending to draw away from the securing nails and to work loose, as well as being imperfectly applied owing to the inevitable distortion.

I have found that a heel lift may be produced perfectly or substantially flat throughout its major body portion and including its

entire rear portion, and by molding and vulcanizing the same with the forward corner tips turned up at a proper angle, the lift as nailed to its seat will lie closely and evenly against the seat without tendency to pull away and without distortion. This is for the reason that the only parts of the lift where there is any appreciable tendency to pull away from the seat are at the forward corner portions, and as these are pressed against the heel seat and flattened these corner portions of the lift are caused to press tightly against the supporting base so as to make a close joint around the corner portion of the lift, preventing dirt from getting thereunder and allowing the natural resiliency of the rubber to press the same back in place whenever the corners come in contact with obstacles. At the same time the resilient pressure of these corner tips is not sufficient to have any appreciable effect in tending to press the lift as a whole away from its seat and the major body portion of the lift lies perfectly flat against its seat without any distortion or tendency to pull away from its securing nails. The foregoing and other objects and advantages of the invention will more fully appear from the following detailed description, and the distinctive features of novelty will be there- after pointed out in the appended claims.

Referring to the drawings:

Fig. 1 is an elevation of a heel lift embodying the invention, viewing the wear surface thereof;

Fig. 2 is a front view thereof;

Fig. 3 is a central longitudinal section on line 3—3 of Fig. 1; and

Fig. 4 is a side view.

The major body portion of the lift including its entire rear portion is preferably made perfectly flat, this being the portion designated 10. In the molding of the lift the breast or forward corner tip portions 11, 12 are turned up at a substantial angle. The extent of the corner portions thus turned up is preferably, though not necessarily, determined by lines drawn from the longitudinal axis or transverse center 13 of the breast edge of the lift diagonally backward to a point 14 which is spaced from the front corners 15 of the lift the same distance that these corners are from the point 13,—i. e., the lines 13, 14 from which the tips are inclined are at approximately a forty-five de-

90

110

gree angle to the front edge of the heel at its central point 13. By turning up the tips along these forty-five degree diagonal lines, it will be noted that the two sides 13, 15, 5 and 14, 15 of each tip will remain symmetrical and of equal length regardless of the extent to which the lift may be trimmed down in fitting it to the heel seat. The extent to which these corner tips are turned 10 up may be varied according to the nature of the material and as preferred, but I preferably for the size of heel shown which is an 11-12 size, i. e., with the dimension from each corner 15 to the transverse center 13 15 about one and a half inches, make the points 15 offset with respect to the flat surface of the portion 10 about one-eighth inch, other sizes being in correspondence therewith. I may produce on the surface of the lifts 20 definite lines 13, 14 which may be grooved into the body of the rubber to a greater or less extent, this slightly weakening and predisposing the material to bend as the tips are flattened, along these definite lines. I 25 also preferably, though not necessarily, make the tip portions 11, 12 substantially flat in their inclined relation from the lines 13, 14. The invention is however not to be understood as limited in these structural details 30 and in general the present embodiment is to

be understood as merely illustrative and not restrictive, reference being had to the appended claims rather than to the foregoing description to indicate the scope of the invention.

35

Having described my invention, what I claim as new and desire to secure by Letters Patent is:

1. A resilient heel lift having a major body and rear portion substantially flat and 40 with breast corner tip portions inclined diagonally upward with respect to the longitudinal axis of the wheel for the purpose stated.

2. A rubber heel lift having its major and 45 rear portion substantially flat, and with front corner tip portions inclined upward with respect thereto along lines extending diagonally rearward from the center of the heel breast.

3. A rubber heel lift having its major and 50 rear portion substantially flat, and with front corner tip portions inclined upward with respect thereto along lines extending diagonally rearward from the center of the heel breast at approximately forty-five degree angles.

In testimony whereof, I have signed my name to this specification.

FREDERICK J. GLEASON.
